UNITED STATES PATENT OFFICE.

JOSEPH GRÜNINGER, OF NEW YORK, N. Y.

AUTOMATIC AIR-COMPRESSOR.

No. 922,694.

Specification of Letters Patent.

Patented May 25, 1909.

Application filed October 31, 1907. Serial No. 399,979.

To all whom it may concern:

Be it known that I, JOSEPH GRÜNINGER, a citizen of the United States of America, and a resident of New York, county and State of 5 New York, have invented certain new and useful Improvements in Automatic Air-Compressors, of which the following is a specification.

This invention has reference to improvements in automatic double acting air compressors preferably run by electricity.

It is the special object of my invention to produce an air compressor which requires no attendance after it has been started, that is, 15 after the current has been turned on. This desirable result is attained by virtue of the novel construction of the air compressor whose cylinders are automatically started and stopped by a novel electric regulator 20 which in turn is actuated by variations of the pressure in the air tank which pressure is produced by the action of the cylinders. By the coöperation of the novel electric regulator with the other parts of the compressor 25 neither current nor motive power is expended unless the compressor is in actual operation except to note that the compressor must be oiled about once a week. Incidental to this main object the cost of construction has been 30 kept low by making the most of the parts of the compressor of cast iron. Owing to the construction of the present compressor its weight is very light being about one-third of the weight of similar compressors formerly 35 used. Accordingly the compressor occupies little space but none of its parts come in contact with each other during operation. Furthermore it has been sought to secure novelty and attractiveness in appearance so as to 40 make the compressor a neat and desirable article which may be mounted under a glass case in a conspicuous place, and a worm gear is advantageously used in connection with the small motor whereby liability to derange- 45 ment is reduced to a minimum, all as will be fully described hereinafter in connection with the accompanying drawing in which:

Figure 1 represents in front elevation partly in section on line 1, 1 of Fig. 2 an air 50 compressor with electric regulator which embodies in desirable form the present improvements. Fig. 2 is a top view of same. Fig. 3 illustrates the compressor in side elevation seen from the right of Fig. 1 partly in 55 section on line 3, 3 of Fig. 2, and Fig. 4 is a

rear view with certain parts omitted and partly in section on line 4, 4 of Fig. 2 showing in detail the electric regulator.

Similar characters of reference denote like parts in all the figures. 60

The automatic air compressor is mounted on a substantial frame *a* which for the preferred size is but 11 inches square while the compressor mounted thereon raises the total height to about 10 inches. Two cylinders *b*, 65 *b'* are mounted on the base plate *a'* of the frame.

The pistons of the cylinders, are connected to a walking beam *c* which is mounted on a substantial post or standard *d* bolted to the 70 base plate *a'* of the frame.

The pistons are of novel construction. The piston proper *p'* is relatively short and surrounded by a cup washer *p²* of leather which is slantingly cut off at the bottom end. 75 On the top of the piston there is secured a device *p³* which is not completely air tight.

The shaft *c'* of the walking beam extends inwardly beyond same and a lever or arm *e* is mounted thereon as shown in Fig. 2. 80 This lever *e* connects with a pitman *f* which extends downward and is connected to a crank *g* mounted on a shaft *h* of the worm wheel *i*. The worm wheel shaft is mounted in suitable bearings on the main frame. Said 85 worm wheel *i* meshes or gears with a worm *j* mounted directly on the shaft *k* of the power motor *l* which is inclosed in a suitable casing secured to the base plate *a'* of the frame.

The power motor *l* is preferably an electric 90 motor which runs at a relatively high speed.

To the bottom of each cylinder a tube *m* is secured which communicates with the interior of same. A valve device is screwed on the bottom end portion of said tube shown in 95 section in Fig. 1. This device consists of a suction valve *v* through which the air passes into the cylinder when the piston ascends. The cup washer *p²* of the short piston proper is then pressed against the inner walls of the 100 cylinder making it air tight while the cup-shaped device *p³* of metal prevents the washer from dislocating and at the same time acts as a guiding device for said piston. When the piston descends the suction valve 105 *v* closes and the air is compressed in the usual manner, passing through the pipe *m* and sidewise into an annular space *n* which communicates with the space below the pressure valve *v'* lifting same and allowing 110

the air to pass through the tube o into the pressure tank. Both valves may be easily taken out for inspection and cleaning.

The electric regulator is actuated by the 5 variations of the pressure in the air tank. For convenience this device is preferably in communication with the tube leading to the pressure tank near the valve devices so as to have this tube within the frame of the 10 compressor but this is not shown on the drawing.

The electric regulator is mounted on a support cast directly on the main frame. It is shown in section in Fig. 4. A circular incision q is cut into the support and a pipe r 15 screwed therein from below. This pipe communicates on the one hand with the small space created by the incision in the support and on the other hand with the pressure tank or the tube leading thereto. A membrane 20 or diaphragm s of suitable material, of rubber for instance, is placed on the support and a small cylinder or housing t screwed on the support securing thus the membrane tightly. The fretted sleeve t' extends into the top of 25 the housing and an open cylindrical spring u is located within the housing and sleeve. Through the spring passes a rod u' having 30 secured to its lower end a small piston u^2 whose upper surface bears against the spring while its lower rests on the membrane s . A lever w supported in the fulcrum w' of an arm which is cast on the housing t connects loosely 35 with the rod u' . The lever extends upward and then horizontally over the power motor. At its end there is a pivot connecting with a downward lever w^2 which carries on its lower 40 end a segmental gear y pivoted to a short rod y' which is guided in the main frame. A star gear y^2 constantly revolves right above the eccentric gear y . The pivot of the eccentric gear carries a cam having a contact z which contacts with a second contact z' when 45 the pump is running.

By virtue of the fretted sleeve within the 45 housing the cylindrical spring may be more or less compressed whereby the pump is adjusted to any desirable number of pounds of pressure within certain limits. For pumps of high pressure the construction remains 50 the same as described save that the pistons are made of smaller diameter.

When the motor is started the pump will work until the pre-determined pressure in the tank has been attained. As soon as the 55 pressure in the tank slightly exceeds the desired number of pounds the membrane s of the regulator is forced upward together with the piston u^2 resting on it. The rod connected to the piston forces up the lever w 60 whereby the eccentric gear is also raised and

engages the star gear which constantly revolves. The star gear moves the eccentric gear to the left whereby the cam with contact z is raised upward and the electric circuit broken. The lever w is quite long 65 therefore any slight rise of the small piston and piston rod readily actuates the electric device located at its free end to which the eccentric gear is attached and the gear moving the eccentric gear raises the one contact 70 quickly a considerable distance whereby the electric circuit is broken and the pump stopped. When the pressure in the tank falls below the predetermined number of pounds the membrane, small piston with rod 75 and lever w descend and with them the eccentric gear and contact z which falls back on the contact z' and reestablishes the electric circuit whereby the motor is again started. Thus the pump gives an even pressure no 80 matter how great the rush of business may be.

By the quick removal of the one contact from the other sparking between same is reduced to a minimum. The absence of sparks is of great importance for the reliable 85 working of the air compressor.

I claim as my invention:

1. In a double acting air compressor, an electric regulator consisting of a small cylinder and piston with membrane below, a 90 lever attached to the piston rod, a segmental eccentric gear in connection with the free end of the lever, a constantly revolving star gear above the segmental gear, a contact on the segmental gear, and a stationary 95 contact.

2. In a double acting air compressor, an electric regulator, a support on which said regulator is mounted, a circular incision in 100 said support, a pipe screwed therein connecting with the incision in the support and the pressure reservoir, a flexible membrane on the support, a small cylinder thereon securing the membrane tightly, a fretted sleeve extending from the top into the housing, a cylindrical spring within the latter, a rod passing through the spring, a piston secured to said rod at its lower end bearing against the spring and the diaphragm, a lever movably secured on the piston rod, a 105 segmental gear on the other end of the lever, a star gear constantly revolving upon the segmental gear, a contact on the segmental gear, and a stationary contact.

Signed at New York, N. Y., this 29th day 115 of October, 1907.

JOSEPH GRÜNINGER.
